UNITED STATES PATENT OFFICE.

ERVIN W. McCULLOUGH AND TRULY NOLEN, OF INDIANAPOLIS, INDIANA.

DEWATERING VEHICLE.

Application filed May 15, 1924. Serial No. 713,543.

This invention relates to a dewatering device for garbage hauling vehicles and the like.

The chief object of this invention is to 5 improve vehicles for hauling garbage and the like by providing the same with suitable means for permitting the water and the liquids to be separated from the garbage solids and be maintained separate following 10 separation.

The chief feature of the invention consists in providing a compartment-forming construction adjacent the bottom, which 15 compartment-forming construction is adapted to sustain a part of the load of the vehicle; and in so sustaining said load automatically separate from the same the liquid content and permit its collection in the lower compartment formed by said construction, 20 from which the liquid can be readily removed without the simultaneous removal of the solids content.

The full nature of the invention will be understood from the accompanying drawings and the following description and 25 claims:

In the drawings, Fig. 1 is a side elevational view of a garbage collection vehicle. Fig. 2 is a longitudinal sectional view with the invention incorporated therein and is taken in the plane of line 2—2 of Fig. 3 and in the direction of the arrows. Fig. 3 is a transverse sectional view of the vehicle body and is taken on the line 3—3 of Fig. 2 and in 30 the direction of the arrows. Fig. 4 is a diagrammatic view of a portion of the vehicle bottom and the compartment-forming construction showing the same in the loaded and unloaded positions. Fig. 5 is a view similar to Fig. 3 and of a modified form of the 35 invention. Fig. 6 is a view similar to Fig. 4 and of the modification shown in Fig. 5.

It has been experimentally determined 40 that the most economical way of handling garbage or similar material is to separate the water content from the solids content, following which separation the solids content may be subjected to any desired form of treatment for garbage disposal purposes. 45 The most efficient method of such separation is to cause the separation of the liquid from the solids content substantially at the time that the material is collected. When a sufficient quantity of liquid content has been 50 separated, the vehicle may be positioned adjacent any convenient manhole or sewer and

the liquids discharged therein, following which additional material may be supplied to the vehicle, provided the solids content supported thereby does not exceed the capacity of the vehicle. 60

The provision within a collection vehicle, suitable for garbage and the like, of a load-sustaining compartment-forming member automatically separates the liquids from the 65 solids content of garbage and the like, due to vehicular vibration and bumping of the vehicle in its movement from house to house and to the garbage handling plant. If the liquid content has not been discharged previously, or if it has been discharged and additional liquid has been separated from the 70 garbage material, the vehicle when received at the plant is permitted to discharge said liquid contents prior to the discharge of the 75 solids content. One form of the invention is conventionally illustrated herein, and consists of a vehicular framework 10 provided with the supporting wheels 11 and with other usual vehicular parts. The vehicle 80 herein illustrated may be adapted for animal or power-draft purposes and also may be of the trailer type, without departing in any way from the invention herein disclosed. The vehicle frame 10 adjacent the rear end 85 is provided with a pivot 12 which pivotally supports upon a horizontal axis the vehicle body which herein is shown comprised of an end wall 13, a pair of side walls 14 which may or may not be parallel and a bottom 15, 90 which see Fig. 3 is disclosed as pitched or inclined toward the center for drainage purposes. The side walls 14 instead of being parallel as herein illustrated may be also pitched inwardly toward the bottom or in 95 any other way. The back of the body thus formed is closed by a suitable plate or end 16, which herein is shown positioned at an angle to the vertical, and the angle is such that when the body is appropriately tilted 100 upon the pivot 12, the end 16 is inclined downwardly from the horizontal equal to an angle sufficient to permit the ready discharge of the garbage material. All of the foregoing is old in the art and forms no part 105 of the present invention.

The body previously described is preferably relatively non-leakable, and within said body there is provided a load-sustaining compartment-forming screen construction. 110 Herein said screen construction is shown composed of a single plate which is formed

arch or V-shaped providing the sides 17 and 18, said plate having the perforations 19 therein. If desired, the plate may be suitably reenforced by longitudinal braces or 5 transverse braces or ribs, but herein the same is not illustrated. The plate compartment-forming member is adapted to be hinged along one longitudinal edge by a plurality of hinge means, such as the hinges 20. 10 Herein three of such hinges are illustrated, but the number may be increased or decreased at will. The other or opposite end of the V-shaped plate is adapted to bear upon the bottom 15 on a line substantially 15 opposite the hinge axis. The dotted lines in Fig. 3 illustrate one position of the compartment-forming member when tilted into cleaning position. It will be noted that the hinge axis is parallel to the longitudinal axis 20 of the body, but transverse to the pivotal axis of the body.

The compartment-forming construction previously described may extend from the front end 13 to the rear end 16 of the body 25 and forms a covered trough having any desired capacity. This trough constitutes also a collection compartment for the liquid and it has been experimentally determined that the capacity of one barrel for the average 30 vehicle capacity of the type of vehicle herein disclosed is sufficient. It will, of course, be readily understood that a compartment-forming construction is not to be necessarily restricted to the V-shaped or angular outline 35 but a curved, corrugated or other conformation could be readily substituted for that herein disclosed and function substantially as well. The V-shaped plate herein disclosed, however, constitutes the simplest type 40 of construction, for nothing more is required than the hinges and the plate. No bearing flanges are necessary, although the same may be provided at the free end of the compartment-forming construction or at the hinge 45 edge or at both edges. It will, of course, be understood that any suitable mechanism may be provided for tilting the body from the full line position shown in Fig. 2 into the dotted line position.

50 Reference will now be had to Figs. 3 and 4. In these figures there is illustrated one form of a load-sustaining compartment-forming construction, and the same is illustrated as a V-shaped perforated plate. As 55 shown clearly in Fig. 4 the full line position indicates the normal or non-loaded position of the construction when the vehicle contains little or no load. The dotted line indicates a possible position of the compartment-forming construction when the vehicle 60 is fully or heavily loaded and the plate is yieldable. It will be readily apparent that there may be relative movement between the plate and the body of the vehicle, which

movement varies with the vehicular vibration and bumping. Thus, the volume and the shape of the compartment formed by the load-sustaining construction may vary from time to time. Such vibration will cause an automatic separation of the liquids from the 65 solids content of the garbage material or the like.

The liquids separated from the garbage material leaving the solids content positioned within the main portion of the vehicle body is trapped in the liquids compartment so formed, and provision is herein made for releasing said separated liquid by providing a valve. The valve is herein indicated by the numeral 21, and the same is 70 of the molasses-cock type, for it has been found that this is substantially the only type of valve which will permit the 75 discharge of liquid from the compartment formed within the vehicle body and substantially seal the outlet therefrom when the valve is closed under all conditions. The general run of valves will not always substantially seal the outlet from drippage. This drippage not only is unsanitary but 80 causes complaints from the householders by reason of the odor of the drippage, discharged upon the roadway and fly nuisance resulting therefrom.

85 From the foregoing description, it will be apparent that the load-supporting screen forms two compartments, the larger being the upper compartment and the smaller being the lower compartment and adapted to contain the solids and the liquid contents 90 respectively upper and lower referring to the load centers. With this automatic separation there is secured increased capacity for the vehicle body, for the solids material may be piled in the center of a body to a 95 height greater than the top wall or edge of said body. This heaping, therefore, permits the collection and transportation of a greater amount of material than heretofore has been possible. If desired, such heaping 100 can be substantially prevented by providing suitable covers for the body. These covers are old in the art and also form no part of the present invention.

105 Another advantage of the use of the invention consists in the automatic separation of the liquids from the solids so that when the garbage is discharged into the vehicle by the collector, the same is not discharged into a water mixture, but is discharged upon a 110 relatively solid mass. Therefore, slopping, splashing, and spillage is substantially eliminated, and the public health is safeguarded from these unsanitary conditions.

115 Another advantage of the use of the invention is that the separation of the liquids content from the solids content reduces or secures the practical elimination of ferment-

tation and decomposition of the garbage material. Thus little offensive odor is created.

Another advantage of the use of the invention consists in the separation of the liquids from the solids, and in such separation a greater amount of free grease is recoverable with the liquor than ordinarily is recoverable from the usual garbage material without reduction treatment. Increased grease yield is due to other causes, such as the elimination or reduction of splashing and due to the decreased fermentation.

Another, and perhaps the most important feature of the invention, consists in the separation of the solids from the liquid and the retention of the solids material in a form that is in better condition for subsequent garbage reduction than heretofore has been possible. All of the foregoing results, therefore, as well as many others which have not been enumerated are due directly or indirectly to the automatic separation of the liquid content from the solids content of the garbage material or the like, which occurs substantially at the time of the collection.

In Fig. 5 there is illustrated a modified form of the invention, and in this form the bottom 115 is shown flat, although it may be otherwise formed and connected thereto are the sides 114. Due to the peculiarities of the chassis upon which this relatively non-leakable body has been mounted and of the shape of the body, it has been difficult to retain a valve in position centrally of said body. Therefore, there has been provided two plates, one indicated by the numeral 117 and the other by the numeral 118. The plate 117 is anchored by hinge means 119 and the plate 118 is anchored by hinge means 120, thereby forming two compartments which may be parallel with each other, and each of which is provided with a valve 121, although if desired the two compartments may be suitably joined and one valve control the common discharge. The action of this modification is identical with the first modification previously described. The preferred construction is that illustrated particularly in Figs. 2 to 4, because said modification requires a minimum number of parts.

While the invention has been described in great detail in the foregoing specifica-

tions, the same is to be considered as illustrative and not restrictive in character. Many modifications of the specific form of the foregoing invention will undoubtedly suggest themselves to those skilled in the art, but all of these modifications are considered to be within the broad purview of the invention, reference being had to the appended claims.

The invention claimed is:

1. In a dewatering vehicle, the combination of a vehicle frame, a relatively non-leakable elongated body having a load receiving and discharge mouth and tiltably supported upon an axis transverse to the body axis and tiltable for discharge of the tank contents from the mouth and including an opening in its lowest portion constituting the sole liquid discharge therefrom, and a load-sustaining compartment-forming screen positioned within the body and extending longitudinally thereof substantially from end to end and having its longitudinal edges associated with the body and constituting the sole support for said screen, said screen being hingedly supported upon an axis transverse to the body pivot axis and forming a compartment drained by said opening.

2. In a dewatering vehicle, a body, a screen plate bent at substantially right angles longitudinally to provide a load-sustaining member of substantially V-shape arranged in inverted position upon the bottom of said body and extending at right angles to the tilting direction of the latter, said plate being of narrow width so as to expose a relatively great area of the bottom to the load, and hinges connecting one longitudinal edge of said plate with the bottom of said body.

3. A device of the character defined by claim 1, characterized by the body bottom being relatively flat and the screen plate being hinged to the bottom of said body so as to leave a relatively large area of said flat bottom exposed to the load and having portions of said plate disposed at an angle to said bottom to form a free channel therewith.

In witness whereof, we have hereunto affixed our signatures.

ERVIN W. McCULLOUGH.
